United States Patent Office

Des. 227,504
Patented June 26, 1973

227,504

CASING FOR A CAMERA OR THE LIKE

Paul Wentworth Lang, Hollywood, Calif., assignor of a fractional part interest to Michael H. Du Pont, Los Angeles, Calif.

Filed Feb. 22, 1972, Ser. No. 228,454

Term of patent 14 years

Int. Cl. D16—01

U.S. Cl. D61—1 B

Fig.1.

Fig.2.

Fig.3.

FIG. 4.

FIG. 5.

FIG. 6.

FIG. 7.

FIG. 1 is a perspective view of a casing for a camera or the like showing my new design;

FIG. 2 is a top plan view thereof;

FIG. 3 is a right side elevational view thereof;

FIG. 4 is a bottom plan view thereof;

FIG. 5 is a left side elevational view thereof;

FIG. 6 is a front elevational view thereof;

FIG. 7 is a rear elevational view thereof.

I claim:

The ornamental design for a casing for a camera or the like, substantially as shown.
